ATTORNEYS

UNITED STATES PATENT OFFICE.

WILLIAM D. FUREY, OF BALTIMORE, MARYLAND.

HOSE SUPPORTER.

Application filed May 31, 1923. Serial No. 642,593.

To all whom it may concern:

Be it known that I, WILLIAM D. FUREY, a citizen of the United States, and a resident of Baltimore, in the State of Maryland, 5 have invented certain new and useful Improvements in Hose Supporters, of which the following is a specification.

My present invention relates generally to hose supporters, and more particularly to 10 hose engaging clasps utilized in connection with hose supporters of various natures, my foremost and general object being the provision of a clasp which will avoid certain known disadvantages to which those clasps 15 now in use are subject.

Clasps for supporting hose commonly include a button and a loop, the latter having an elongated button receiving channel closed at its outer end, and the inner end of which 20 communicates with a comparatively wide button entering opening. My improved clasp embodies the same parts, but contemplates a somewhat different construction of each part and a somewhat different coaction 25 thereof in the effective position, the difference in structure of the parts having for its object more simple economical manufacture among other things and the difference in the coaction of the parts having for its object 30 to avoid frequent tearing of the hose by distributing the strain which in the ordinary clasp is concentrated at a single point.

The usual hose clasp embodies a loop 35 formed of sheet metal and involving in its production a number of operations resulting in a shaped final structure and the outer end of whose button receiving channel is closed and receives thereagainst the outer end of the button so that as frequent test has 40 shown the point of strain upon a garment engaged by the clasp is concentrated between the outer end of the button and the outer end of the button receiving channel. Moreover the button in the most commonly 45 known and used device which is attached to the button carrying web is a molded product involving in its manufacture certain costly operations which I seek to avoid and necessitating more or less expensive attaching means which my invention avoids.

In the accompanying drawing which illustrates my present invention and forms a part of this specification,

Figure 1 is a front view illustrating the 55 practical application of my invention,

Figure 2 is a perspective view of my im-

proved clasp showing the parts in effective position,

Figure 3 is a similar view illustrating the clasp in engagement with a section of hose, 60

Figure 4 is a vertical longitudinal section taken centrally through the clasp,

Figure 5 is a detail perspective view showing the parts of the clasp in detached relation, and 65

Figure 6 is a front elevation illustrating a slightly modified form.

Referring now to these figures I have shown the clasps in Figure 1 as supported by tapes 10, for engagement with hose 11, 70 the clasps being generally indicated at 12, but it is quite obvious that the clasps may be utilized with various other means forming hose supporters as a whole of various different types other than that shown. 75

The clasp constituting my invention and generally indicated at 12 in Figure 1 is composed of parts best seen in Figure 5, including a button 13, button holding plate 14 and button engaging loop 15, the latter according to my invention being formed of wire, preferably steel wire having sufficient rigidity to retain its given shape and having outer spaced parallel extensions 16 forming therebetween a button receiving channel 17, 80 the extreme outer portions of these side extensions being bent upwardly at right angles thereto in the form of an arch 18 so that the outer end of the button receiving channel 17 is thus open. 90

The inner ends of the extensions 16 join the spaced apart sides 19 of the loop 15 by inclined portions 20 which serve to guide the button 13 and the button entering opening between the loop sides 19 into the button receiving channel 17, the inner ends of the loop sides 19 being bent at right angles toward one another and into abutting relation to form a connecting bar 21. 95

Thus by means of the connecting bar 21 at the rear or inner end of the loop 15, the latter may be connected to one side of a laterally elongated tab or strap receiving loop 22 by means of a tubular shackle 23 which thus flexibly supports the loop 15 of the clasp 105 with respect to the strap or tab receiving loop 22, and around which shackle may be extended the inner end of the button supporting web 24 whose outer portion has a pocket 25 receiving the button holding plate 14. 110

The button 13 as proposed by my inven-

tion is preferably of rectangular form with square cut ends and longitudinally grooved sides 26 so that it is obvious that the button thus formed may consist simply of a cut off 5 section of an elongated strip having grooved sides so as to avoid the necessity of molding each button separately and thereby greatly reduce the cost of production.

It is the usual practice to secure buttons 10 by forcing the same on to headed studs up-standing from the button attaching plates, but in view of the fact that at neither end of my improved button comes into actual clasping relation with the hose I am thereby enabled to attach the button in a more economical manner by the provision of plate 14 having central longitudinally alined lugs 27 which are integral therewith and spaced apart a distance equal to the length of the 20 button 13, and which taper to upper or outer pointed ends the latter of which may be bent into and embedded within opposite ends of the button 13 so as to rigidly and effectively hold the button in place upon the outer portion of the web 24 through one side of the pocket 25 of which it is to be understood that the button attaching lugs or spurs 27 are extended.

The button 13 is of such width that the 30 space or distance between the bases of its side grooves 26, into which the parallel extensions 16 of the loop 15 upon opposite sides of the button receiving channel 17 are received, is but slightly less than the width 35 of the button receiving channel of the loop, so as to clasp the hose at spaced points between the button sides and the extensions 16, leaving that portion of the hose lying between its engaged portions free to yield with 40 respect to the clasp whereby the strain will be distributed and clearly prevented from concentrating at any particular point, for instance at the outer end of the loop, which is a distinct disadvantage by virtue of the 45 fact that it so frequently tears or otherwise breaks the hose at this particular clasping point, as seen most clearly by a comparison of Figures 2 and 3.

Not only does the loop 15, constructed as 50 described constitute a more simple inexpensive loop than those now commonly made of sheet metal, but its wire construction admits of much more ready provision for an open space at the outer end of the button receiving channel.

In Figure 6 I have shown a slight modification in respect to the particular shape of the button. The button as shown in this figure may have parallel side grooves and 60 still be gradually enlarged toward its outer end as indicated at 13^a with the object in

view of clasping hose with a greater holding power, the remaining portions of the clasp shown as a whole in Figure 6 being the same as those previously described in connection 65 with Figures 1 to 5 inclusive.

I claim:

1. A clasp for hose supporters including a button receiving loop, a button to enter and coact with said loop, a button supporting web, and a button attaching plate within the outer portion of the web, having spaced upstanding spurs between which the button is endwise seated, said spurs having upper deflected ends projecting into and embedded 75 within the ends of the button.

2. A clasp for garment supporters including a button receiving loop and a button to enter and coact with said loop, said button being generally of rectangular form, having 80 square cut ends and parallel grooves in its opposite sides, the said loop having spaced parallel portions forming between them a button receiving channel and adapted to enter the grooves of the button and having 85 its outer end, at the outer end of the channel, offset from contact with the outer square end of the button.

3. A clasp for hose supporters including a button, and a loop having an elongated button receiving channel, the sides of which coact with the sides of the button, and the outer end of which is open for the freely yielding movements of that portion of a 90 garment between the portions thereof engaged by the sides of the button and the sides of the button receiving channel of the loop.

4. A clasp for hose supporters including a 100 loop having a button receiving opening and parallel side portions forming a button receiving channel therebetween and the outer 105 ends of which are deflected to form a connecting arch and button abutment leaving the outer end of the button receiving channel open, and a button to enter the loop, said button being movable in the channel of the loop and engageable with the said abutment arch to limit its outward movement in the channel.

5. A clasp for hose supporters including a 110 button, and a loop with which the button coacts, said loop formed of wire having spaced apart sides provided with rear angular abutting ends and with forward parallel 115 and inwardly offset extensions, the ends of said loop at the forward ends of said extensions being deflected upwardly and forming a button abutting arch which leaves the button receiving channel between said extensions open at the forward end thereof.

WILLIAM D. FUREY.
